UNITED STATES PATENT OFFICE.

HENRY F. DOBBIN, OF NEW YORK, N. Y., ASSIGNOR TO WESTERN ELECTRIC COMPANY,
INCORPORATED, OF NEW YORK, N. Y., A CORPORATION OF NEW YORK.

SELECTOR-SWITCH.

1,205,520.

Specification of Letters Patent. Patented Nov. 21, 1916.

Application filed June 10, 1916. Serial No. 102,900.

To all whom it may concern:

Be it known that I, HENRY F. DOBBIN, a citizen of the United States, residing at New York, in the county of New York and State 5 of New York, have invented certain new and useful Improvements in Selector-Switches, of which the following is a full, clear, concise, and exact description.

This invention relates to automatic 10 switches for use in telephone systems, and more particularly to the type of switch in which a brush is first positioned in operative relation to a group of contacts and is then advanced to make connection with a desired 15 contact in such group.

The object of the present invention is to provide a structure in which a terminal bank of the panel type may be used in conjunction with one or more brush sets, such 20 brush sets having both a vertical and a rotary motion, the vertical motion being applied first. The general construction of a switch having means for providing motion as above described, is shown in Patent No. 25 815,176 of Keith, Erickson and Erickson, issued March 13, 1906.

A feature of the invention is an arrangement by which a brush set is caused to travel over terminal sets in one group of the contact bank during one series of rotary steps, and a second brush set is caused to travel 30 over terminal sets in a second group of the contact bank during the next series of steps.

An additional feature of the invention is 35 the placing of all the tip terminals of the lines of a group in one division, while the ring terminals of the group are arranged in a second division, there being a separate brush for each division.

40 A structure having the above mentioned features has the advantages to be obtained from the use of the simpler and cheaper panel type contact bank, and at the same time simplifies the construction of the brush shaft, since only two brush sets per shaft are needed, as against the five or ten brush sets needed per shaft in all previously known arrangements suitable for use with terminal contact banks of the panel type.

50 The preferred form of the switch shown in Figures 1 to 3 of the drawings is arranged for use in a two-wire multiple telephone system such as shown in an application of Charles L. Goodrum, Serial No. 35,326, filed 55 June 21, 1915, and is therefore shown as

having only two contacts in each terminal set and only two brushes in each set. It is to be understood, however, that this switch may be provided with a greater number of terminals and brushes in each set if 60 the switch is to be used in a three- or four-wire system.

The invention may be better understood from the following description, reference being had to the accompanying drawings. 65

In the drawings, Fig. 1 is a front elevation of a panel type terminal bank showing a brush carrying shaft in its normal relation to such bank; Fig. 2 is a plan view of the same, and shows the angular relation 70 of the brush sets on the shaft; Fig. 3 is a detail view in elevation showing the construction of the terminal bank.

Brush sets 2—2' and 3—3' are rigidly mounted on a shaft 1, which is arranged to 75 be stepped in both upward and rotary directions, the upward motion being applied first. The mechanism by which motion is given to the shaft 1 may be of any suitable character, the general construction of this 80 type of operating mechanism being shown in the previously mentioned Patent No. 815,176.

The terminal bank is divided horizontally 85 into four sections, the two lower sections containing the tip and ring terminals of the first fifty lines of a group of one hundred, while the two upper sections contain the tip and ring terminals of the remaining fifty lines of the one hundred group. That 90 is, sections 4 and 5 contain the multiple terminal sets of fifty lines and are arranged to be served by the lower brush set of a given brush-carrying shaft. The tip brush 3 of the set swings over tip terminals in 95 section 5, while the ring brush 3' swings over ring terminals of corresponding lines in section 4. The brush set 2—2' and sections 6 and 7 have a similar relation.

As best shown in Fig. 2, the angular relation between the two brush sets is such that during the first five rotary steps the brush set 3—3' engages multiple terminal sets in the sections 4 and 5, and during the second five rotary steps the brush set 2—2' 105 engages multiple terminal sets in sections 6 and 7.

Each section of terminals is divided into ten levels, each level containing a series of five terminals. The individual contacts 110

8 of each series are offset, as best seen in Fig. 3, so as to lie in the same plane. This method of offsetting the terminals is disclosed in an application by H. F. Dobbin, Serial No. 46,855, filed August 23, 1915. The reason for locating the ring and tip terminals in different sections of a group is to allow the series of terminals to be more readily offset.

10 Between adjacent series of five terminal strips is interlaced a conductor strip, insulated from the multiple strips, which has a connection to ground for the purpose of eliminating crosstalk. This method for preventing crosstalk is described in an application by O. F. Forsberg, Serial No. 87,581, filed March 29, 1916.

As shown in Fig. 2, the contacts of the multiple strips may be so arranged that contacts are provided on both faces of the panel, in which case the bank would serve a series of line finder switches on one face, and a series of connector switches on the opposite face.

25 What is claimed is:

1. In an automatic switch, a contact bank of the panel type, terminal sets therein divided into a plurality of groups, a brush shaft, a plurality of brush sets thereon, and means for actuating said brush shaft in a vertical direction and then in a rotary direction, the arrangement being such that one of said brush sets begins rotary travel over one of said groups of terminal sets at the time a preceding brush set completes its rotary travel over another one of said groups of terminal sets.

2. In an automatic switch, a contact bank of the panel type, terminal sets therein divided into two groups, a brush shaft, two brush sets thereon, and means for actuating said brush shaft in a vertical direction and then in a rotary direction, the arrangement being such that the second of said brush sets begins rotary travel over the second of said groups of terminal sets at the time the first brush set completes its rotary travel over the first of said groups of terminal sets.

3. In an automatic switch for use in telephone exchange systems, a contact bank of the panel type, terminal sets therein divided into groups, the tip and ring terminals of said terminal sets being located in separate sections of a group, a brush shaft, a plurality of brush sets thereon, equal in number to

the number of groups of terminal sets, and means for actuating said brush shaft in a vertical direction and then in a rotary direction to move said brush sets successively into engagement with successive groups of terminal sets.

4. In an automatic switch for use in telephone exchange systems, a contact bank of the panel type, terminal sets therein divided into two groups, the tip and ring terminals of said terminal sets being located in separate sections of a group, a brush shaft, two brush sets thereon, and means for actuating said brush shaft in a vertical direction and then in a rotary direction to move said brush sets successively into engagement with successive groups of terminal sets.

5. In an automatic switch for use in telephone exchange systems, a contact bank of the panel type, terminal sets therein divided into a plurality of groups, each of said groups being served by a brush set individual thereto, each of said groups comprising a plurality of series of terminal sets, the tip contacts of each series being offset so as to lie in the same plane, the ring contacts of each series being similarly offset, but lying in a different section of the group, a brush shaft carrying said brush sets, and means for moving said shaft vertically and then rotatably, each vertical step moving the brush sets to the successive levels of the series of terminal sets in the groups respectively served by said brush sets.

6. In an automatic switch for use in telephone exchange systems, a contact bank of the panel type, terminal sets therein divided into two groups, each of said groups being served by a brush set individual thereto, each of said groups comprising ten series of terminal sets, the tip and ring contacts of each series being located in separate sections of the group, each series of five tip contacts being offset so as to lie in the same plane, each series of ring contacts being similarly offset, a brush shaft carrying said brush sets, and means for moving said shaft vertically and then rotatably, each vertical step moving the brush sets to the successive levels of the series of terminal sets in the groups respectively served by said brush sets.

In witness whereof, I hereunto subscribe my name this 8th day of June A. D., 1916.

HENRY F. DOBBIN.
